UNITED STATES PATENT OFFICE.

GEORGE H. FOSTER, OF HARTFORD, CONNECTICUT, ASSIGNOR TO UNDERWOOD TYPE-WRITER COMPANY, OF NEW YORK, N. Y., A CORPORATION OF DELAWARE.

TYPEWRITING-MACHINE.

1,368,620.

Specification of Letters Patent. Patented Feb. 15, 1921.

Application filed June 19, 1919. Serial No. 305,224.

To all whom it may concern:

Be it known that I, GEORGE H. FOSTER, a citizen of the United States, residing at Hartford, in the county of Hartford and 5 State of Connecticut, have invented certain new and useful Improvements in Typewriting-Machines, of which the following is a specification.

This invention relates to typewriting machines, and is herein disclosed as applied to 10 an Underwood standard typewriting machine, in which the types strike against the front side of a platen in printing.

In writing machines like the Underwood 15 typewriting machine and others, which are known as visible writers, the typist has the great advantage of seeing the written work. It is, however, often advantageous to conceal the written work, either because it is 20 confidential and therefore should be hidden from view of those who might make it public property, or because the typist wishes to conceal the written work, as, for example, in practising some systems of typewriting.

25 According to the present invention, the typewriting or other machine may be provided with a device in the form of a shield or screen, which is adapted to be positioned so that it may keep much or all of the writing covered, or may be swung to ineffective 30 position, leaving the writing open to view. The device is herein disclosed as comprising a thin sheet-metal screen, which is journaled upon a rod so that it may be swung to vari-

35 ous angles, said rod being mounted upon brackets by means of swinging arms, thus permitting the screen to be swung on the swinging arms either to the effective position or to the ineffective position at the rear of 40 the typewriter carriage. The screen advantageously swings on its journals close to the front bar of the carriage if adjusted to the angle at which it conceals the whole of the writing. It may, however, be swung to other 45 angles to leave open to view one or more lines of writing. The rod on which the screen is swung may also carry upper front feed-rolls, which are adapted to guide the typewritten sheet rearwardly over the top of the platen.

50 Other features and advantages will hereinafter appear.

In the accompanying drawings,

Figure 1 is a perspective view, largely dia-

grammatic, of an Underwood typewriter 55 carriage, showing the present invention as applied thereto.

Fig. 2 is a perspective detail, showing the mounting of the rod.

Fig. 3 is a perspective view of one of the 60 swinging arms.

Fig. 4 is a sectional side view showing the screen in two positions in which it substantially conceals the writing line.

Fig. 5 is a view similar to Fig. 4, but 65 showing the screen swung to allow several lines of writing to be visible.

Fig. 6 is a similar view, showing the screen swung to ineffective position at the 70 rear of the carriage.

In the usual Underwood typewriting machine, the traveling carriage 10 includes a platen frame 11, in which is journaled a platen 12 by means of its axle 13 which passes through end plates 14 and 15 of the 75 platen frame. As the typewriter carriage travels along, it carried with it a work-sheet 16 passed around the platen to enable types 17 to print upon it at the writing line, which falls substantially at the top of the usual 80 wing scales 18. In order to hold the work-sheet 16 upon the platen, it passes down over a rear paper table 19, and is held against the platen by the usual feed-rolls 20 and 21, and the end of the work-sheet is 85 bent rearwardly over the top of the platen by top front feed-rolls 22 which will be described later.

In writing upon the work-sheet 16, with the parts positioned, as shown in Fig. 1, the 90 typist has the writing in view, the typist looking over the front bar 23 of the typewriter carriage. In order to conceal the lines above the one actually written, a shield or screen 24 may be provided, held by means 95 of screws 25 to brackets 26 splined to a rod 27 extending across the front of the shift frame.

In order to support the rod 27 there are provided arms 28 and 29 pivoted to their 100 brackets 30 and 31 formed as the turned-up ears of plates 32 and 33, which are adapted to be held to the top cover plates 34 and 35 of the ends 14 and 15, by means of screws 36 adapted to fit into the usual screw holes 105 which hold the cover plates 34 and 35 upon the ends 14 and 15. The ears or brackets 30 and 31 rise near the rear ends of the cover

plates, so that the arms 28 and 29, when raised up and swung over rearwardly, will have their ends projecting considerably to the rear of the typewriter carriage, as is clearly shown in Fig. 6. The arms 28 and 29 may support the feed-rolls 22.

To enable these arms to support the rod 27, each arm has held fast thereto by a screw 38 a small bracket 39, which is riveted to a journal bracket 40 having two ears or turned up ends 41, in which latter the rod 27 is journaled. In order to keep the rod 27 from turning too easily in the ears 41, there is provided a friction roll 42 bearing against the outside of the shaft or rod 27 and pressed firmly thereagainst by a flat spring 27a. The friction of the spring upon the roll 42 is sufficient to hold the rod 27 at any angle to which it is set, and, therefore, to hold the screen 24 at any predetermined or desired angle.

In order to support the screen 24, there may be provided any suitable number of brackets 26. For a typewriting machine of ordinary width the number of brackets usually need not exceed two. To enable the arms 28 and 29 to carry the feed-rolls 22, the arms are provided with inwardly-extending elbows 43 having downwardly extending ends 44, in which latter is fast a transverse rod 45 upon which the feed-rolls 22 are journaled, there usually being one feed-roll 22 between the center of the platen and each end thereof, the rolls, however, being slideable on the rod 45 to suit the various widths of paper which may be used. To enable the rolls 22 and the screen 24 to be swung upwardly without the necessity of pulling on the screen itself, there may be provided at each elbow 43 an upwardly-extending curved finger-hold 46. To enable the shield or screen 24 to be shifted to either the Fig. 4 position, in which it conceals all the writing, or the Fig. 5 position, in which it conceals only part of the writing, there is provided a finger-piece 47 fast upon the shaft or rod 27, thus enabling the rod to be easily turned in its journals 40. The screen rod 27 is adapted to be held firmly, either at its front position, Fig. 4, or its rear position, Fig. 6; and to accomplish this, there is pivoted to an extension or ear 48 of each bracket 30 and 31 an arm 49, which presses an extension 50 thereof outwardly, thus forcing the arms 28 and 29 downwardly, since the pivots 51, by which the arms 49 are connected to the arms 28 and 29, are normally below the level of the pivots in the ears 48. To give the extensions 50 a spring action, each extension is formed as comprising a sleeve 52, which encloses a coil spring 53 against which the end 54 of the arm 49 bears as a plunger.

As will be clearly seen from Figs. 1 and 4, the screen 24 is forcibly detained at a substantially fixed front position by the springs

53, because the feed-rolls 22 bear upon the platen 12. When the rod 27 is swung upwardly and rearwardly, the arms 28 and 29 pass the dead center of their pivots, and then the springs 53 force the arms rearwardly and downwardly until they rest upon the rear end 55 of the top plate. In order to permit the arms 28 and 29 to thus swing freely, they are provided with collars 56, which space them inwardly from the ears 30 and 31 so that they stand completely clear of the arms 49.

Variations may be resorted to within the scope of the invention, and portions of the improvements may be used without others.

Having thus described my invention, I claim:

1. In a front-strike typewriting machine, the combination with a revoluble platen and a platen frame, of a work-sheet shield, arms pivoted upon said frame to enable said shield to be swung to the rear of the frame, spring tension arms pivoted upon said frame at points removed from the pivot points of the first arms, said tension arms adapted to hold said shield either at effective position or at ineffective position at the rear, and a rod upon said first arms upon which said shield is rotatably mounted to enable it to be swung at various angles.

2. In a front-strike typewriting machine, the combination with a revoluble platen and a platen frame, of a work-sheet shield, arms pivoted upon said frame to enable said shield to be swung to the rear of the frame, a rod upon said arms upon which said shield is rotatably mounted to enable it to be swung at various angles, guide rolls to bear upon the platen above the printing line, and a roll rod supporting said rolls and fast to said arms.

3. In a front-strike typewriting machine, the combination with a revoluble platen and a platen frame, of a work-sheet shield, arms pivoted upon said frame to enable said shield to be swung to the rear of the frame, spring tension arms pivoted upon said frame at points removed from the pivot points of the first arms, said tension arms adapted to hold said shield either at effective position or at ineffective position at the rear, guide rolls to bear upon the platen above the printing line, and a roll rod supporting said rolls and fast to said first-named arms.

4. In a front-strike typewriting machine, the combination with a revoluble platen and a platen frame having ends, of rolls to run upon the platen, a rod upon said frame and carrying said rolls, a shield to swing on said rod into position to cover all but a desired number of written lines upon the work-sheet, brackets upon said ends, and arms swinging upon said brackets and carrying said rod.

5. In a front-strike typewriting machine,

the combination with a revoluble platen and a platen frame having ends, of a rod supported by said ends, a front bar forming part of the carriage carrying the frame, a 5 flat stiff screen upon said bar and adapted to be swung to and from the front bar to conceal more or less of the written lines, journals in which said rod is carried, and a finger-piece fast to said rod to swing the 10 screen.

6. In a front-strike typewriting machine, the combination with a revoluble platen and a platen frame having ends, of a rod supported by said ends, a front bar forming 15 part of the carriage carrying frame, a flat stiff screen upon said bar and adapted to be swung to and from the front bar to conceal more or less of the written lines, journals in which said rod is carried, a finger-piece fast to said rod to swing the screen, 20 arms carrying said journals, ears upon said ends to which said arms are pivoted, and other arms pivoted to said ears and connect-

ed to the first arms to detain the screen in its adjusted position. 25

7. In a front-strike typewriting machine, the combination with a revoluble platen and a platen frame having ends, of a rod supported by said ends, a front bar forming part of the carriage carrying the frame, a 30 flat stiff screen upon said bar and adapted to be swung to and from the front bar to conceal more or less of the written lines, journals in which said rod is carried, a finger-piece fast to said rod to swing the 35 screen, arms carrying said journals, ears upon said ends to which said arms are pivoted, other arms pivoted to said ears and connected to the first arms to detain the screen in its adjusted position, and front 40 feed-rolls connected to said first arms and adapted to limit their throw.

GEORGE H. FOSTER.
